UNITED STATES PATENT OFFICE.

WALTER P. MURPHY, OF CHICAGO, ILLINOIS.

CENTERING DEVICE.

1,178,666.

Specification of Letters Patent. Patented Apr. 11, 1916.

Application filed July 13, 1911. Serial No. 638,393.

To all whom it may concern:

Be it known that I, WALTER P. MURPHY, a citizen of the United States, and a resident of the City of Chicago, in the county 5 of Cook and State of Illinois, have invented a new and useful Improvement in Centering Devices, of which the following is a specification.

My invention relates to centering devices 10 for draw-bars in railway cars, and consists in an improvement in the form of carry-iron and means for supporting it from the car.

My invention further consists in the de- 15 tails of construction of the various parts of my improved centering device whereby they are readily assembled in working position, and as readily taken apart for repairs or replacement should such necessity occur while 20 the car is in service.

My invention further consists in the ar- 25 arrangement of parts as shown in the accom- companying drawings forming a part of this specification, as will be more fully set forth in the description thereof, and particularly pointed out in the appended claims.

In the drawings, in which like characters are used to designate like parts throughout the several views, Figure 1 is an elevation of 30 my improved centering device and carry-iron as seen from the end of the car, a portion of the end sill of the car being shown; Fig. 2 is a part top plan of the same, partly in section on the line 2-2 of Fig. 1, showing 35 the ends of the draft sills of the car also; Figs. 3 and 4 are vertical sections through the end sill on the lines 3-3 and 4-4 of Fig. 1, and showing the ends of the draft sills of the car in side elevation; Fig. 40 5 is a side view of a supporting link; Fig. 6 is an end view of the roller carry-iron, of the forms illustrated in Figs. 1 to 4; Fig. 7 is an elevation of a modified form of my invention, showing a portion of the end sill 45 of the car; Fig. 8 is a part top plan view of the modification shown in Fig. 7, partly in section on the line 8-8 in Fig. 7, showing the ends of the draft sills; and Figs. 9 and 50 10 are vertical sections through the end sill of a car fitted with the modified form of my invention shown in Fig. 7 on the lines 9-9 and 10-10 of Fig. 7, showing the ends of the draft sills in side elevation.

In the drawings, 1 is the end sill of the car extending across from one side sill to the other and bringing the ends of the draft

girders or sills 2 on either side of the center line of the car. An angle 3 is riveted to the inside of the end sill near its top, the other leg of the angle being attached to the top 60 flanges of the draft sills, as shown.

The striking casting 4 is positioned outside the end sill to receive blows and shocks due to coupling with other cars or striking obstacles, and is securely fastened to the 65 end sill by means of a flange 5, and also rigidly attached to the ends of the draft sills, practically forming extensions thereof, to give additional strength to resist shocks and endure hard service.

The striking casting is provided with 70 downward extensions 6 at its lateral edges, these extensions being in line with and secured to the ends of the draft sills by means of rivets 17. At their upper edges these extensions 6 are bifurcated and recessed to provide bearings 7 for the links 8 supporting the carry-iron 11, on which the draw- 75 bar rests.

In the form of my invention illustrated in 80 Figs. 1 to 6, the links have trunnions 9 at their upper extremities, and elongated slots or loops 10 at their lower extremities in which the end bearings 14 of the roller carry-iron 11 are supported. The carry- 85 irons are retained in the links by elliptical flanges 13 having the same general contour as the slots 10 so they may be inserted through the slots. It is evident, that once in place the carry-iron cannot be withdrawn 90 from its supports without raising it off its bearing in the loops and turning it so the flanges 13 stand vertical. The end bearings of the carry-iron are enlarged in the middle and rounded off at the ends, forming ellipsoids, which provide line contacts in the loops whatever the angle of oscillation of the links. The central cylindrical portion of the carry-iron is flanked by flanges 16, between which the draw-bar is positioned. 95

The extensions 6 are spaced such a distance apart that one of the flanges 16 of the carry-iron will bring up against the inside face of one or the other of the extensions at the limit of lateral oscillation of the draw-bar. 100 Between the flanges 16 and bearings 14 are cylindrical necks 15, which ride in notches 12 in the lower edges of the extensions 6 and prevent the carry-iron from swinging in the direction of the longitudinal motion 105 of the draw-bar. These necks 15 are long enough to remain in engagement in the

notches 12 at the limits of lateral movement of the carry-iron. The end bearings of the roller carry-iron are made of small diameter relatively to the diameter at the point of support of the draw bar in order that the friction in the bearings of the roller may be less than that between the draw bar and roller, and the draw bar will roll on the roller carry-iron.

10 In the form of the device illustrated in Figs. 7 to 10, the end sill 1 and draft girders 2 are secured together directly, the reversing of the end sill so the flanges face in instead of out enabling the angle iron to be dispensed with. The striking casting 18 is provided with a flange 19 for attachment to the end sill and downward projections 20 on either side of the center line in line with the draft girders and attached thereto. 15 Links 21 are pivotally supported from bearings 22 in the striking casting by pins 23 passing through eyes in the upper ends of the links, and the lower ends of the links are formed with loops 24 in which are arranged the end bearings 25 of the roller carry-iron 26. The loop portions of the links have cheeks 27 arranged to bear against the plane ends of the enlargements 28, between which the draw bar is positioned, and 20 elliptical ends 29 of the roller carry-iron. This arrangement insures that the links shall be maintained in central alinement with respect to the end bearings 25 of the roller carry-iron. The substitution of enlargement 25 (Fig. 7) for neck 15 (Fig. 1) allows the draw bar to strike against the projection 20 of the striking casting. In Fig. 7 the ellipsoid is on hanger 21 instead of the end bearing of the carry-iron as before described.

My improved draw bar centering device arrangement entirely eliminates friction on the under side of the draw bar, as it is free to oscillate sidewise, and it permits the draw bar to roll in and out, and therefore the wear on the top of the carry-iron and bottom of the draw bar is prevented. Wear at this point is troublesome, as it results in lowering the draw bar and dropping it out of proper alinement, and it is difficult to take it up. Also wear at this point of the coupler (called the shank) is fatal since it weakens it at a vital point, causing the "head" to be broken entirely off by sudden impacts. 55 Moreover my improved centering device provides a very free support for the draw bar, enabling it to accommodate itself to service conditions quickly, and always returning it to central position when uncoupled.

In railway cars where draft sills or girders extend beyond the end sill, the end portions of said draft sills or girders may be made to form trunnion pockets or pin journals.

Obviously, the device admits of considerable modification without departing from my invention. Therefore, I do not wish to be limited to the specific constructions and arrangements shown.

What I claim is:

1. A roller carry-iron for draw bars having a cylindrical portion adapted to support the draw bar and end bearings of less diameter than said first mentioned cylindrical portion, in combination with oscillating links forming end bearings therefor, said end bearings being ellipsoidal in form to provide line contact bearings between the links and carry-iron at various relative angular portions.

2. A supporting link for a roller carry-iron, said link having end loops adapted to receive the journals of said carry-iron, and said end loops being provided with protruding cheek portions adapted to engage the end of the carry-iron.

3. In combination with a roller carry-iron having end journals and noncylindrical end flanges, links adapted to receive said journals, said links being provided with orifices substantially the same in contour as the said end flanges.

4. In a railway car, draft sills provided with extensions beyond the end sill, supporting links in line with said draft sills, a roller carry-iron with its ends rotatably mounted in said links and engaging said extensions, said carry-iron being oscillatory crosswise of the car and adapted for rolling engagement with a draw bar.

5. The combination of a car underframe, a carry-iron pivotally suspended therefrom for movement crosswise of the car, said carry-iron comprising a roller portion lengthwise arranged thereon and adapted to support a draw-bar, said pivotal suspending means yieldingly holding said carry-iron in central alinement with the car underframe, and means on said carry-iron adapted to maintain the draw-bar in central position on said roller.

Signed at St. Louis, Missouri, this 11th day of July, 1911.

WALTER P. MURPHY.
